UNITED STATES PATENT OFFICE.

ROBERT HUNTER AIKEN, OF WINTHROP HARBOR, ILLINOIS.

METHOD AND APPARATUS FOR FORMING REINFORCED CONCRETE TUBULAR STRUCTURES.

No. 863,485.

Specification of Letters Patent.

Patented Aug. 13, 1907.

Application filed February 11, 1907. Serial No. 358,760.

To all whom it may concern:

Be it known that I, ROBERT HUNTER AIKEN, a citizen of the United States, residing at Winthrop Harbor, in the county of Lake and State of Illinois, have invented certain new and useful Improvements in Methods and Apparatus for Forming Reinforced Concrete Tubular Structures, of which the following is a specification.

This invention relates to the construction of reinforced concrete chimneys, stacks, and the like, and involves forming tubular sections in a horizontal position, to be afterward superposed in vertical position and rigidly united, forming a tubular structure of any desired height.

15 In the accompanying drawings, Figure 1 is a side elevation, partly in section, showing the forming apparatus and a formed column section. Fig. 2 is a cross section of the same devices. Fig. 3 is a side elevation of a portion of a chimney or column, parts being broken away to show interior construction.

In forming the tubular sections, I employ two spiders, A, removably fixed upon a revolvably mounted horizontal shaft B at a distance from each other approximately equal to the length of the proposed section. To the arms of each spider, and between the two spiders, is secured an annular steel plate, C, provided with a flange C' extending toward the companion spider. The flanges of the two plates are correspondingly, perforated at short intervals to receive steel rods, D, 25 parallel to the shaft, extending from one plate to the other and bent at their ends to enter the perforations in the flanges, the bent ends being threaded, if desired, to receive nuts to hold them in place. Around the cage formed by these rods are wound wires, E, 30 at some distance apart, the plates, rods and wires forming the reinforcement for the concrete to be added.

Within the cage is placed a laterally curved plate, F, extending substantially from one spider to the other and located at a distance within the inner margin of 40 the annular plates dependent upon the thickness desired for the concrete wall to be formed. The width of the curved plate is such that it forms any desired fraction of the inner circumference of the section to be formed, that fraction, in the drawings, being about one 45 fifth. This curved plate is supported from the shaft by arms F' of adjustable length projecting from hubs or sleeves, G', revolvably fixed upon the shaft. The parts thus far described being in readiness, the curved plate F is brought directly above the shaft and concrete is 50 placed upon it in sufficient quantity to completely cover the reinforcing portions to the desired depth, the wires, for example being covered to the depth of an inch or more. The concrete is carefully rammed so that no voids may remain, the thinness of the material-

layer and its horizontal position making it easy to insure perfect results. The annular steel plates form the ends of this mass, but its lateral margins may be left more or less irregular. When the mass thus put in place has set slightly, the cage is turned through a distance about equal to the width of the mass, the curved plate or form is again brought to position directly over the shaft, and another segment similar to and continuous with the first is formed in like manner. This process is repeated until the whole section is completed, and the section is then allowed to further set until it 55 may be handled without danger of breakage, when it is removed from the shaft, the spiders are detached, and the section is rolled away to be stored until fully hardened, or until it is needed for use.

The shaft may be rotated by means of gearing I without novelty, and accidental rotation may be prevented by one or more pawls J.

The spiders may be of unequal size if it be desired to have the stack tapered, and different spiders and forms may be used of course, for sections of different 75 sizes. It follows that base sections may be made larger than the others, and obviously the sections may be varied from cylindrical or frusto-conical form.

In erecting a stack or tower, the sections may be superposed in succession, as shown in Fig. 3, the annular 80 contiguous end plates being rigidly connected by bolts placed in the holes which served for securing the plates to the spiders, small cavities being left for the insertion of the bolts and afterward filled with cement, so that no metal is left exposed.

When the sections are not too large to allow shipment, they may be made at the quarry and shipped on cars or otherwise, and the time required in erecting a stack, for example, is extremely short, and the space required for the work is insignificant.

The construction readily admits of forming windows or other openings in the structure, or of building the wells double by using concentric sections of differing diameters, and the continuous steel frame lends itself perfectly to protection against lightning. It may also 95 be observed that the finish or surface of the work may be simple or elaborate, and in either case it may be better done because the surface is in a practically horizontal position, and besides, the whole is integral and homogeneous there being no imperfectly fitted 100 surface layer as there is when the wall is formed between form surfaces of wood or metal and plastered after the forms have been removed.

What I claim is:—

1. The method of forming concrete stack sections which 105 consists in revolvably mounting a metal reinforcing frame upon a horizontal axis, placing within the frame a removable concrete receiving form, molding upon this form above

the axis of the frame a segment of the stack section, partially rotating the frame from time to time and adding other segments until the section is completed, and detaching the section from its mounting and said form.

5. 2. The method of forming concrete stack sections which consists in revolvably mounting a tubular, metal, reinforcing frame with its axis in a horizontal position, mounting within said frame a removable, concrete-receiving form in position to support concrete above the axis of the frame, molding a concrete segment upon said form and above said axis, rotating the frame to move said segment aside, restoring the form to proper molding position, again molding concrete upon the form to widen the segment already formed, continuing the process until the section is completed, and separating the completed section from the supporting structure, substantially as set forth.
3. The method of forming concrete stack sections which consists in forming a tubular cage of metallic reinforcing members, arranging the cage, in horizontal position, for rotary movement, securing within the cage a removable, concrete-receiving form, molding upon the form above its axis a concrete segment enveloping the corresponding portion of said cage, moving said segment aside by rotating

the cage, adding concrete in like manner to progressively widen the segment until the section is completed, and removing the completed section from the supporting structure.

4. The combination with a revolvably mounted horizontal shaft, of a spider fixed to the shaft, a second parallel spider removably fixed to the shaft at some distance from the first, and an independent segmental form adjustably mounted upon the shaft between the spiders and less distant from the shaft than are the ends of the spider arms.

5. The combination with a revolvably mounted horizontal shaft, of two spiders detachably fixed upon the shaft at some distance from each other and adapted to support a metal reinforcing form extending from one to the other, an independent, concrete-supporting form between said spiders, and arms of adjustable length supporting said form and revolvably adjustable about said shaft.

in testimony whereof I have signed my name to this specification in the presence of two subscribing witnesses,

ROBERT HUNTER AIKEN.
